TOILET KIT

James Huntley, Philadelphia, Pa.

Application May 9, 1936, Serial No. 78,753

2 Claims. (Cl. 132—81)

My invention relates broadly to toilet kits and more particularly to a portable and compact kit for carrying toilet articles which may be secured in a fixed position when the kit is not in use.

5 The object of my invention is to provide a compact, durable and attractive cabinet adapted to be conveniently used for housing toilet articles such as shaving cream, tooth paste, ointments, tooth brushes, razor, blades, toilet water, styptic 10 pencil and such incidentals as are necessary to effect a satisfactory toilet for a man or woman.

Another object of my invention is to provide an inexpensive and simply constructed toilet kit containing the aforesaid toilet articles in an orderly 15 assembly which can be readily carried on trips undertaken by any means of transportation and which can be easily attached to any plane surface for immediate use.

Other and further objects of my invention 20 reside in the construction and the organization of the toilet kit of my invention, as set forth more fully in the accompanying drawing, in which:

Figure 1 is a front elevation of the toilet kit with its door ajar.

25 Figure 2 is an enlarged longitudinal section of the toilet kit taken on line 2—2.

Figure 3 is an enlarged horizontal section of the toilet kit taken on line 3—3.

Figure 4 is an enlarged sectional view of the 30 discharge orifice for the toilet water container.

Referring to the drawing, in which like reference numerals indicate like parts, 1 designates the hinged door and 2 the hollow back to which the door 1 is attached. The door 2 is preferably 35 fabricated from one piece of sheet metal or any other desirable material and consists of a forwardly projected rim portion 3 constituting the top, the sides and the bottom of the door and, when the door is closed, of the cabinet itself.

40 The door 1 is rectangular in general outline and not only carries several of the toilet accessories but serves importantly to shield the remaining articles attached to the back 2 in order that they may at all times be kept in a clean and sanitary 45 condition. The door 1 can be securely fastened to the back 2 by means of any appropriate clasp or catch. The front panel 4 of door 1 is highly polished to function as a plane mirror in order to assist one in the preparation of his toilet. On 50 the inside of the panel 4 is attached a holder 5 which can accommodate two or more tooth brushes 6.

On the forward side of the back 2 is mounted a holder 7 which consists of a plurality of clips 8 55 which are adapted to hold securely in position a

shaving brush 9 and two dispensers 10 of plastic toilet preparations, e. g. tooth paste, shaving cream, etc. The aforesaid dispensers 10 have been completely described in my Patent Number 2,052,296, issued Aug. 25, 1936. 5

Mounted obliquely on the forward side of the back 2 and above the holder 7 is a receptacle 11, designed to hold the razor blades 12. Above the receptacle 11 is rigidly attached the clip holder 13 for the purpose of receiving the razor 14. The 10 back 2 is somewhat recessed at 15 to accommodate the guards 16 of the razor 14. Within the hollow back 2 is the clip 18 which provides a mounting means for the bottle 19 containing some liquid 15 toilet preparation. The bottle 19 of conventional design and not an integral part of my novel kit is fitted mouth downward into the flared metal flange 20 which is cushioned by the rubber gasket 21. The flange 20 is joined to the right angle tube 22 through the end of which is inserted a conventional valve 23. In use the application of 20 pressure by means of the hand to the plunger 24 will induce the flow outwardly of a small quantity of the toilet preparation contained in the bottle 19. The hollow back 2 with its flaring side members 25 is preferably fabricated of a single sheet 25 of material and is adapted to slide between the counterpart inclining side members 26 of the wall plate 17 and to rest securely upon the upwardly inclined bottom edge 27 of the aforesaid wall 30 plate. The wall plate 17 may be attached to the wall or plane surface by means of suction cups or hooks 28.

The manner of using the cabinet or kit will be 35 readily understood by reference to Figures 1 to 4 without indulging in an extended explanation. The kit is designed primarily to serve as a convenience in hotel and bath rooms and to properly 40 keep together the articles required for shaving or other toilet operations in a special place provided for them.

I have found the toilet cabinet practical in its construction and arrangement and highly convenient in use and, while I have described a preferred embodiment of my invention, I desire that 45 it be understood that modifications may be made and that no limitations upon my invention are intended other than are imposed by the scope of the appended claims.

What I claim as new and desire to secure by 50 Letters Patent is as follows:

1. A cabinet for holding toilet requisites comprising a rectangular door having a top, a bottom, sides and a front, said front adapted externally to be used as a plane mirror and internally to 55

receive and to support toilet articles; a hollow back to which said door is hingedly engaged, said back provided with a plurality of clips and supports to receive sundry toilet requisites and recessed inwardly from its front surface to receive a conventional safety razor; a wall plate having inwardly inclining side members and an upwardly inclining bottom member and adapted therefore to be slidably engaged with said back, said wall plate being further adapted to be attached by any means to a plane surface; and a means whereby said door and said back can be locked to shield said toilet requisites enclosed.

2. A cabinet for holding toilet requisites comprising a rectangular door having a top, a bottom, sides and a front, said front adapted externally to be used as a plane mirror and internally to receive and to support toilet articles; a

hollow back to which said door is hingedly engaged, said back provided on its front surface with a plurality of clips and supports to receive sundry toilet requisites and on its rear surface with a supporting clip and orifice fixture extending through and beyond said front surface and recessed inwardly from said front surface to receive a conventional safety razor; a wall plate having inwardly inclining side members and an upwardly inclining bottom member and adapted therefore to be slidably engaged with said back, said wall plate being further adapted to be attached by any means to a plane surface; and a means whereby said door and said back can be locked to shield said toilet requisites enclosed.

JAMES HUNTLEY.
